(57) **CLAIM**

The ornamental design for a body temperature reducing under shirt, as shown and described.

DESCRIPTION

FIG. 1 is a perspective view of a body temperature reducing under shirt, showing my new design;

FIG. 2 is a front elevational view of the invention;

FIG. 3 is a rear elevational view of the invention;

FIG. 4 is a left-side elevational view of the invention, the right-side elevational view being a mirror image thereof;

FIG. 5 is a top plan view of the invention; and,

FIG. 6 is a bottom plan view of the invention.

In the drawings, the broken lines showing a man in FIG. 1 are included for the purpose of illustrating the invention in use, and form no part of the claimed design; the broken lines depicting stitching on the pocket structures of the under shirt in FIGS. 1–4 form part of the claim.
